No. 699,182.

Patented May 6, 1902.

E. D. JOHNSTON.
OYSTER TRIMMING MACHINE.

(Application filed June 10, 1901.)

(No Model.)

UNITED STATES PATENT OFFICE.

EDWARD DUDLEY JOHNSTON, OF NEW YORK, N. Y.

OYSTER-TRIMMING MACHINE.

SPECIFICATION forming part of Letters Patent No. 699,182, dated May 6, 1902.

Application filed June 10, 1901. Serial No. 63,949. (No model.)

To all whom it may concern:

Be it known that I, EDWARD DUDLEY JOHNSTON, a citizen of the United States, and a resident of New York, county of New York 5 and State of New York, have invented certain new and useful Improvements in Means for Preparing Bivalves for Opening, of which the following is a specification, reference being had to the accompanying drawings, forming 10 a part thereof, in which similar characters of reference indicate corresponding parts.

This invention relates to means for preparing bivalves for opening; and its main object is to provide means for removing a portion 15 of the shell of an oyster, clam, or similar bivalve preparatory to opening the same. In preparing such bivalves for opening I first cut off a portion of each shell and then clear away the portion so cut off before the bivalve 20 so prepared is carried forward to be opened; and in carrying out my invention I make use of a mechanism by means of which bivalves are fed by a traveling carrier to a cutter or saw which saws off a portion of each shell; 25 and this portion so sawed off is separated from the major portion of the bivalve or oyster by a clearing device or stripper and deposited at one side of the machine, while the bivalve so cut is carried forward by the traveling belt or conveyer and may then be operated 30 upon to open the same.

In the drawings, Figure 1 is a side elevation of a machine for preparing bivalves for opening in accordance with my invention. 35 Fig. 2 is an end elevation of the same. Fig. 3 is a sectional detail of the saw and the clearing device, the section being taken in line xx , Fig. 2. Fig. 4 is an enlarged detail illustrating in perspective the construction of the conveyer.

In carrying out my invention I mount the various operating parts on a suitable frame, such as A, the main members of which are a base 2, side pieces 3 and 4, which may be 45 X-shaped, as shown in the drawings, or any other suitable form, and a table 5 over which the bivalves are caused to travel by a suitable conveyer.

The operating parts may be actuated in any 50 desired manner; but in this case I prefer to actuate them by foot-power through a treadle, such as t, pivoted on the base 2 and operating

a crank-shaft 6, journaled in bearings in the side frames 3 and 4. This shaft may, however, be operated by a belt (not shown) passing around a band-wheel 8, which may be used when power is accessible. The shaft has thereon in this case two gears, one of which is a small pinion 10 and meshes with a large gear 12, secured to a shaft 13, journaled 55 in suitable bearings, one in the side frame 4 and the other in a hanger 15, while the other gear-wheel is a larger gear or sprocket wheel 17, operating a sprocket-chain 18, which in turn drives a sprocket-pinion 19, carried by a 60 shaft 20, journaled in the side frames 3 and 4 just below the table 5. This shaft has thereon a balance-wheel H, by means of which the machine may be started and which gives shaft 20 sufficient momentum to keep the machine 65 in operation. Said shaft may also carry one or more saws, two being shown herein at s and s', for the purpose of sawing the ends of two bivalves.

All the parts which operate upon the bivalves are preferably duplex, except the clearing device, in order that the two rows of bivalves may be passed through the machine and prepared rapidly; but it is obvious that my invention could also be embodied in a single machine.

The saws s and s' project a suitable distance above the table 5 and the bivalves are brought adjacent thereto by a pair of conveyers or belts, such as B and B', which will preferably 75 be constructed as shown. These conveyers are operated from the shaft 13 by means of sprocket-wheels, one of which is seen in Fig. 1 at 25, and pass over guide-sprockets or sprocket-pinions, such as 26 and 27, disposed 80 in pairs at opposite ends of the table 5, these sprocket-pinions being mounted in bearings on brackets 28 and 28', detachable from the table 5.

The conveyers B and B' will usually be 95 roller-chains having side links 30, connected and spaced by rollers 31, which roll on the table 5 and between guide rails or plates 5^a, and each carrier or conveyer belt will preferably have two parallel chains constructed in this 100 manner and connected by retaining devices, such as r, for holding the bivalves in place on the conveyers. These retaining or holding devices may be rigidly secured to the chains,

as clearly shown in Fig. 4, and will be disposed at suitable intervals along the conveyers, each holding device being usually a plate of proper form secured to the chains of the 5 conveyer and embodying flat surfaces r^a and extensions F^b , slightly curved forwardly, and in which the bivalve may find lodgment and be securely held during the sawing operation. Said plate is coated with rubber or other flexible substance, as r^c .

For the purpose of holding the bivalves in place during treatment, I have shown at p and p' a pair of presser-rolls, which are peripherally coated with rubber or other flexible material. These may be held in place by half-bearings, such as 36, at the ends of arms, such as 37, pivoted to uprights 38, rising from the table 5, said arms being spring-pressed, as shown at 39, in order to hold these presser-rolls firmly against the bivalves, or the weights, as p'' , may be sufficiently heavy to obviate the use of the springs.

To keep the parts clean during the operation of clipping the bivalves, I drip water on 25 the rolls P and P' by means of a water-tank T , having the faucets t' .

In order to clear away the sawed portions of the bivalves, I prefer to locate between the saws s and s' a clearing device or stripper c , 30 having a hooked end, which will engage the small sawed portions of the shells and prevent the carrying forward thereof by the conveyers, this clearing device being secured to the saw-shaft 20, whereby during the operation 35 of the machine it continuously revolves with the saws, the severed parts of the shells being thrown against a chute q and discharged. This chute is removed from Fig. 2 of the drawings in order not to obscure the working 40 parts of the machine.

In operating the machine the treadle t is operated (or the band-wheel 8 rotated) and power transmitted to the saws s and s' through the sprocket-chain 18, and at the same time 45 the conveyers B and B' are caused to travel across the table 5 from the right to the left, as seen in Fig. 1, by means of the gearing before described. An attendant at the receiving end of the table 5 then places the bivalves or oysters on the roller-chains of the 50 two conveyers B and B' , one bivalve being placed in front of each holding device r on each conveyer as said holding devices reach the receiving end of the table. These bivalves are carried forward by the conveyers 55 until they reach the presser-rolls p and p' , which press the bivalves firmly against the holding devices r , located upon the conveyers, and the inner end of each bivalve is cut 60 off by the saws s and s' and immediately cleared away by the clearing device c , located between said saws. The pressure of the rolls p and p' is not sufficient, however,

to prevent the treated bivalves from being carried forward by the holding devices r , and 65 after the cutting operation each pair of bivalves is carried toward the delivery end of the table and may be removed by another attendant or discharged into a suitable receptacle. 70

Having thus described my invention, what I claim as new, and desire to secure by Letters Patent, is—

1. In a machine of the class specified, the combination, with an endless conveyer and means for operating the same, of a revoluble cutting device, a revoluble clearing device and means for revolving the said clearing and cutting devices, both turning on the same axis, whereby they coact with the conveyer, 80 the cutting device adapted to cut away a portion of the shell of a bivalve carried by the conveyer, and the clearing device adapted to clip and throw off the cut portion of the shell, substantially as shown and described. 85

2. In a machine of the class specified, the combination, with an endless conveyer having holding devices projecting therefrom, each holding device shaped for retaining a bivalve and having a flexible lining, and means for operating said conveyer, of a revoluble cutting device and a revoluble clearing device, both turning on the same axis, and means for revolving them, the cutting device and clearing device coacting with the conveyer, the cutting device adapted to cut away a portion of the shell of a bivalve carried by the conveyer, and the clearing device adapted to clip and clear away the cut portion of shell, substantially as shown and described. 100

3. In a machine of the class specified, the combination, with an endless conveyer having holding devices projecting therefrom, each holding device shaped for retaining a bivalve and having a flexible lining, and means for operating the same, and a flexible presser-roller mounted on the frame for holding a bivalve in place on said conveyer while said bivalve is being clipped, of a revoluble cutting device and a revoluble clearing device, both turning on the same axis, and means for revolving them, the cutting device and clearing device coacting with the conveyer, the cutting device adapted to cut away a portion of the shell of a bivalve carried by the conveyer, and the clearing device adapted to clip and clear away the cut portion, substantially as shown and described. 110 115

In testimony that I claim the foregoing as my invention I have signed my name, in presence of two witnesses, this 3d day of June, 1901.

EDWARD DUDLEY JOHNSTON.
